UNITED STATES PATENT OFFICE.

EMILE ROBIOLE, OF NEW YORK, N. Y.

FIRE-ESCAPE.

SPECIFICATION forming part of Letters Patent No. 622,079, dated March 28, 1899.

Application filed December 29, 1898. Serial No. 700,617. (No model.)

To all whom it may concern:

Be it known that I, EMILE ROBIOLE, of the city of New York, borough of Manhattan, in the county and State of New York, have invented a new and Improved Fire-Escape, of which the following is a full, clear, and exact description.

This invention relates to an improvement in fire-escapes; and the object is to provide a fire-escape in connection with a piece of household furniture and so arranged that the piece of furniture may be easily moved about a room to serve its usual functions and also serve as an anchor for said fire-escape when the fire-escape is thrown out of a window in case of fire.

I will describe a fire-escape embodying my invention and then point out the novel features in the appended claims.

Reference is to be had to the accompanying drawings, forming a part of this specification, in which similar characters of reference indicate corresponding parts in all the views.

Figure 1 is a section on the line 1 1 of Fig. 2 of a fire-escape embodying my invention. Fig. 2 is a partial section and partial rear elevation of the same. Fig. 3 is a section of a portion of the device, showing the position of parts when running the fire-escape out of a window; and Fig. 4 is a partial plan and section on the line 4 4 of Fig. 2.

I have shown the piece of furniture in the form of a chair; but it is obvious that it may be otherwise formed—for instance, to serve as a sofa. The piece of furniture comprises a seat 1, supported on legs 2, which are provided with casters 3. From the seat a back 4 extends upward, and rearward of this back 4 and spaced therefrom is a supplemental back 5. Arranged below the seat is a casing 6, provided at its front with a hinged door 7, and the back of said casing is formed by an extension of the supplemental back 5. To make the piece of furniture sufficiently heavy to serve as an anchor, I attach a weight to the lower portion. This weight is here shown as a plate 8, of iron, secured to the legs 2.

Arranged in the casing 6 is a spindle 9, upon which the flexible fire-escape or ladder 10 is designed to be wound. This spindle 9 has disks 11 at its ends, and at one end it has an

angular socket 12 to be engaged by a suitable winding-crank, which may be inserted through an opening 13, formed in the side wall of the casing. The ladder is made preferably of 55 steel-wire cables or side pieces, to which steel rungs 14 are attached. Normally a portion of this ladder extends up between the backs 4 and 5, and at its outer end it is provided with a heavy weight 15, which normally rests upon 60 the upper end of the back 4 and upon a roller 16, arranged in the upper end of the supplemental back 5.

When not in use as a fire-escape, the several parts will be in the position indicated in 65 Fig. 1, so that the piece of furniture may be easily moved to any desired position about a room. In case of fire, however, the piece of furniture is to be moved up to a window, as indicated in Fig. 3, and the weighted end of 70 the fire-escape thrown out of the window. The heavy weight 15 will cause the fire-escape or ladder to unwind until said weight 15 reaches the ground or other place of safety. As running the ladder directly over the outer 75 edge of the window-sill might interfere with its downward movement, I provide a roller 17, over which it may run. This roller is journaled in the free ends of arms 18, which are pivoted to the upper end of the back 4, and 80 these arms when the device is not in use as a fire-escape will hang downward, as indicated in Figs. 1 and 2. This roller 17 will not only provide for the easy movement of the ladder, but as the connection of the arms 85 with the piece of furniture is inward of the roller 16 the arms will serve as braces to prevent any possible tipping of the chair while a person is going down the ladder. Obviously the piece of furniture may be upholstered 90 and made as ornamental as desired, and, as before stated, it may be made in the form of a chair or sofa.

Instead of a movable piece of furniture a stationary box may be arranged near a window 95 and have the fire-escape wound therein. Of course the box would have a double back, and as it forms a seat it is to be considered as a piece of furniture.

Having thus described my invention, I claim as new and desire to secure by Letters Patent—

1. The combination, with a piece of furniture, having a back and a supplemental back secured to the first-named back, of a roller mounted on the upper end of the supplemental back, a spindle in the lower portion of the piece of furniture, and a flexible fire-escape attached to the spindle and having a portion extended upward between the two backs, substantially as specified.
- 10 2. The combination, with a piece of furniture, having a back and a supplemental back secured thereto, of a roller mounted on the upper end of the supplemental back, a spindle in the lower portion of the piece of furniture, a flexible fire-escape attached to the spindle and having a portion extended upward between the backs, and a weight extended across the fire-escape at its free end, and adapted to rest upon the top of the main back and the roller when the fire-escape is
- 15 wound on the spindle, substantially as specified.
- 20 3. The combination, with a piece of furniture having a back and a supplemental back, of a casing arranged in the lower portion of said piece of furniture, a spindle in said casing, a flexible fire-escape secured to said spindle and having a portion extended upward between the back and the supplemental back, a weight on the free end of said fire-escape, a roller at the upper end of the supplemental back, arms mounted to swing on the back of the piece of furniture, a roller journaled in the free ends of said arms, and a weight in the lower portion of said piece of furniture, substantially as specified.

EMILE ROBIOLE.
